UNITED STATES PATENT OFFICE

WILLIAM N. DAVIS, OF DETROIT, MICHIGAN, ASSIGNOR TO GENERAL MOTORS CORPORATION, OF DETROIT, MICHIGAN, A CORPORATION OF DELAWARE

TOOL BOX

Application filed February 26, 1927. Serial No. 171,214.

This invention relates to automotive vehicles particularly to a tool box and tool box compartment arranged in the dust guard thereof.

5 My novel tool compartment is positioned in the dust guard between the chassis side bar and the running board and occupies the space between two adjacent running board supports. To the lower end of the chassis 10 bar I attach a panel having an outwardly bent lower portion which forms the bottom of the receptacle and with this panel there is associated a second panel attached to the running board at its upper end and having 15 its lower end inwardly flanged to meet the bent portion of the panel attached to the chassis. These meeting ends may or may not be secured together and the receptacle has the usual ends attached in any suitable 20 way.

The front or vertical portion of the dust guard is provided with an enlarged opening having an inwardly offset flanged edge for the purpose of receiving a closure or cover, 25 flush with the outer or vertical portion of the dust guard. This closure has no hinges but rests with its lower edge upon a series of bolts which secure the running board to the dust guard and at its upper edge is provided 30 with a centrally disposed hinged locking member which at its inner side has secured thereto two laterally projecting rods having bent ends which contact with the inside of the upper portion of the dust guard when the 35 closure is in locked position.

Within the receptacle there is located my novel tool box or container the top of which is semi-cylindrical in shape and which has an oblique opening over which is disposed a 40 corresponding oblique cover having a pair of spring handles at its top. This cover is held in place by means of a U-shaped bail in the form of a rod the ends of which are inwardly bent forming pivot pins which are received in corresponding openings in the running board supporting braces. The handle portion of the bail swings onto the cover of the box and rests in depressions in the 45 handles to hold the cover in place.

50 On the inside lower portion of the closure

member there is attached a pair of spring fingers which contact with the tool box cover when the closure is in locked position the purpose of which is to prevent rattling.

My invention is disclosed in the accompanying drawing in which:

Figure 1 is a side view of a portion of the dust guard of an automotive vehicle with my invention applied thereto, the running board being removed.

Figure 2 is a plan view of the structure of Figure 1 but with the outer enclosure broken away for purposes of clearer illustration.

Figure 3 is an end view of Figure 2 looking from the right of the figure but with the end portion of the receptacle removed for purposes of clearer illustration, the sectioned portions being taken substantially on the line 3-3 of Fig. 1.

Figure 4 is an enlarged detailed view of my hinged locking member.

Figure 5 is a section on the line 5-5 of Figure 4.

Figure 6 is a detailed view showing the manner of attaching the running board to the outer side of the receptacle.

Referring to the drawing 10 designates the chassis, 11 the dust guard and 12 the running board of an automotive vehicle. The running board is supported by means of the 80 usual braces 13 and it is in the space between two of these braces that my receptacle is placed.

By referring to Figure 3 it will be noted that I attach to the lower flange of the chassis side bar 10, a panel 14 having attaching flanged tongues 15 and an upwardly directed portion 16 forming the bottom of the receptacle. The flange 15 is secured to the chassis by means of bolts 17.

Attached to the running board by means of bolts 18 is a panel 19 having an inwardly directed flanged portion 20 which overlaps with the outwardly directed portion 16 of the panel 14. These panels 16 and 20 may or may not be secured together as desired at their overlapping portions. The receptacle has the usual ends 21 and 22 which may be secured at any convenient place, and which have bottom end flanges 9 underlapping the 100

portions 16 and 20 of the side panels. The running board supports 13 pass through the receptacle immediately adjacent the ends 21 and 22, and portion 16 has a number of openings (not shown) to serve as a drain.

5 The body of the vehicle rests upon the surface at 23 (Fig. 3) and at the front vertical portion of the dust guard I provide an opening 24 having an inwardly offset flanged edge 25 the depth of which corresponds to the thickness of the closure 26. The flanged edge 25 extends only about the sides and the top edge of the opening 24. At its lower corners the closure 26 is seated in the corners 61 (Fig. 1) of the flanged opening 24 and its lower edge passes over the bolts 18. At its upper central portion the closure is provided with a hinged locking strap 27 pivoted to a reinforcing member 28 positioned at the inner upper edge of the closure and having end bearings 34 for the reception of the locking rods 29 and 30. The strap 27 has secured thereto and projecting laterally therefrom in opposite directions, the two locking rods 29 and 30 having bent ends 31 which strike against and are held in contact with the inside of the upper edge 33 of the dust guard when the closure is in locked position. When the strap 27 is swung upwardly it will swing the rods 29 therewith and remove the bent ends 31 from the path of the upper edge 33, which will permit the removal of the cover and allow access to the interior compartment. The rods 29 are secured to the hinged strap 27 by means of the bent ends 35 which are received within and rigidly secured in openings 36 of the strap 27.

40 The lower portion of the strap 27 projects through an opening 38 in the cover and this strap is provided with an opening 39 for the reception of a lock 40 having a finger 41 on its inner side for engagement with an inwardly pressed cup shaped portion 42 formed on the cover 26. The closure is shown locked in Figure 5 and in this position the locking parts are under spring tension because the strap 27 must be forced into its opening 39 against the tension of the rods 29 and 30 due to the contacting of their ends with the 50 edge 33.

45 Inside this receptacle I place my novel tool box which may or may not be secured therein. This tool box is rectangular at the bottom, and semi-cylindrical at the top as shown at 43. The tool box has an oblique opening 44 extending over the greater portion of the top and over half way down the outer side to a line substantially in the plane of the running board. This opening is closed by an oblique 60 cover 45 having a grooved or flanged edge 46 to shed water and a pair of spring strap handles 47 each having a depression 48 for the reception of the handle portion 49 of a U-shaped bail 60. This bail has its ends inwardly bent as at 50 for reception within

65 openings 51 in the vertical portion of the running board supports 13.

To securely hold the cover 45 in place, the bail 60 is forced into the depressions 48 of the handles 47 so that it may be under tension. This position of the parts is shown in Figure 3 and to remove the cover the bail is swung downwardly onto the running board to the dotted line position. In holding the cover 45 on the box 43, the bail 60 also holds 70 the box in the container or receptacle. 75

The lower inside portion of the closure 26 is provided with spring fingers 52 which contact with the cover 45 of the tool box when the closure 26 is in position, the purpose of 80 which is to prevent rattling of the parts.

Suitable projections 62 are provided to support the lower edge of the closure 26.

I claim:

1. In a tool box for vehicles, an obliquely disposed cover therefor extending across the top and a portion of one side, a handle on said cover, and a swingable member contacting with and extending over said handle and secured to the vehicle to hold said cover on 90 said box.

2. In a tool box for vehicles, an obliquely disposed cover therefor, a groove on the cover edge outside the box, and a member secured to the vehicle for holding the cover on the 95 box.

3. A tool box for vehicles having running board supports, a semi-cylindrical upper portion, an obliquely disposed cover overlapping said box and forming a part of said upper portion, and bail pivoted to the running board supports to hold said cover on said box.

4. In a tool box for vehicles having running board supports, an obliquely disposed 105 cover for said box extending across the top and a portion of one side, a handle on said cover, and a bail having hooked ends pivoted to the running board supports of the vehicle and contacting with said handle to hold said cover on said box.

In testimony whereof I affix my signature.

WILLIAM N. DAVIS.
